UNITED STATES PATENT OFFICE.

FREDERICO MONACO, OF COSENZA, ITALY.

GUITAR.

Application filed March 23, 1926. Serial No. 96,799.

My present invention relates to stringed musical instruments and while of more general application is especially useful in guitars of the type known as French guitars.

5 It is among the objects of the invention to provide a guitar producing an enhanced richness or mellowness of tone without rendering the instrument more bulky, or more delicate or fragile in construction or adding materially to the cost of producing the same.

According to my invention in its preferred embodiment, the face panel of the resonating body is divided into two segments, the segment nearer the handle being superposed 15 over the corresponding parts of the lengths of the strings, and the complementary segment at lower level carrying the tail or anchor piece of the strings. In the preferred embodiment the lower segment is 20 formed with a tongue extending longitudinally to the edge of the base at which the handle is anchored, the fret board extending along the length of said tongue to and outward along the length of the handle. Preferably a resonator mouth piece is interposed 25 between the contiguous transverse edges of the two segments of the face panel and determines a low bridge straddling the strings.

30 Other objects and features will appear as the description proceeds.

In the accompanying drawings in which is shown one of the various possible embodiments of the several features of the invention,

Fig. 1 is a plan view of the instrument;

Fig. 2 is a longitudinal section view taken on line 2—2 of Fig. 1;

Fig. 3 is an elevation view from the lower 40 end of the instrument;

Fig. 4 is a transverse sectional view taken on line 4—4 of Fig. 1, and;

Fig. 5 is a perspective view of the mouth piece.

45 Referring now to the drawings, I have shown an instrument including the substantially conventionally shaped resonating chamber, having a back panel 10 about which extends a side wall 11 to which is secured the shank 12 of the handle provided with the usual head 13 for adjustably anchoring the strings 14 the lower ends of which are conventionally connected to the usual anchor or tail piece 15 mounted on 50 the face of the resonating chamber.

According to the present invention the resonating chamber is modified by dividing the same into two panel segments 16 and 17. The segment 16 extends continuously about the edge of the side wall but terminates 60 preferably at a curved edge 16' extending transversely across the body. The complementary face panel 17 extends at a substantially higher level over the corresponding part of the lengths of the strings as shown. For this purpose the side wall of the base is stepped at 18 for greater height at the part beyond that sustaining the panel segment 16. The segment 16 is provided 65 with a tongue 19 unitary therewith, extending longitudinally of the base and anchored at its end to a cleat 20 at the handle end of the base. The fret board 21 extends not only along the handle but continues along tongue 19 to the curved edge 16' of the panel segment 16. A transverse support cleat 22 is provided for sustaining the median parts of the tongue 19 and of the fret board thereon. The lower curved edge 70 17' of the upper face panel is sustained on a unitary bridge piece 23 extending the entire length of said curved edge and secured at the corresponding edge of the lower panel and serving as a curved resonator mouth piece bridging transversely 75 across the strings and having an effective opening 24 but little wider than the fret board.

The resonator chamber is open not only at its mouth piece 24 but a substantial notch 90 26 is provided in the side wall through which the fret board and strings extend as shown. A transverse cleat 25 also sustains the median part of panel segment 17, and has lugs at opposite side of the fret board 21 that rest upon the cleat 22. By the arrangement disclosed, with the contiguous edges of the panel segments curved as shown, the panel 17 extends over or covers a length of string which is a minimum for the string of highest pitch and a maximum for the string of lowest pitch and is graduated therebetween.

100 A guitar of the construction described produces a sound of sweetness, richness, and mellowness superior to that of an ordinary guitar. Where in ordinary stringed instruments the opening in the face panel of the body serves both for admission of the sound vibrations to be amplified and for exit 105 110

therefrom of the reflected waves, the resonated vibrations originate at portions of the strings within the resonator body, that is at portions other than the exposed segments of the strings that the player plucks and my resonator mouth thus serves primarily only as an exit for the sound waves. By this arrangement also as distinguished from an ordinary guitar the resonated

10 sound is that primarily originating at portions of the length of the strings nearer the middle thereof, and at a substantial distance from the tail piece and this is probably a contributing factor to the superior 15 results produced, as is also the circumstance that the hand of the operator in plucking does not substantially cover or close the resonator mouth as in ordinary stringed instruments. The resonator chamber, it 20 will be seen is open not only at its mouth 24, but also at the notch 26 at the handle end of the side wall, which I find improves the quality and obviates disturbing tone 25 qualities.

25 It will thus be seen that there is herein described apparatus in which the several features of this invention are embodied, and which apparatus in its action attains the various objects of the invention and is well 30 suited to meet the requirements of practical use.

As many changes could be made in the above construction and many apparently widely different embodiments of this invention 35 could be made without departing from the scope thereof, it is intended that all matter contained in the above description or shown in the accompanying drawings shall be interpreted as illustrative and not in a 40 limiting sense.

I claim:

1. A stringed instrument comprising a resonating chamber having a base panel, a side wall, a tail piece supporting face panel 45 segment thereacross, a complementary face panel segment spaced at a greater distance from said base panel and extending over parts of the lengths of strings, and a resonator mouth piece straddling the strings 50 near the contiguous edges of the two segments.

2. A stringed instrument comprising a resonating chamber having a face panel segment extending over part of the length of the strings, a complementary face panel portion having a tail piece sustaining the lower plucked ends of the strings, and a resonator mouth piece straddling the strings and bridging between the contiguous edges of 55 the two panel segments.

3. A stringed instrument comprising a resonating chamber having a base panel, a stepped side wall having a segment at higher level and a segment at lower level, and complementary face panels mounted on the steps

of the side wall, a tail piece sustained on the segment at lower level, strings extending therefrom under the segments at higher level, and a resonator mouth piece extending across the width of the chamber, secured to the two segments near the transverse edges thereof, and presenting a mouth of width less than the chamber and straddling the strings. 70

4. A musical instrument comprising a resonating base having a panel provided with a segment, a handle attached to said base, and provided with a head, a tail piece on said panel and strings connected between said tail piece and said head, said panel segment extending over part of the length of said strings and a bridge substantially at the edge of said segment straddling said strings and determining a resonator mouth of small height and of width less than that of the base. 75 80

5. A guitar comprising a base, a side wall and a handle, a divided closure panel having a lower segment extending over the lower part of the resonator base, a string tail piece 90 supported thereon, a complementary panel section supported on a correspondingly raised part of the side wall and extending over the strings, and a fret board extending along the handle and secured at its inner end to the corresponding edge of the lower 95 panel board segment.

6. A guitar comprising, in combination, a resonating chamber, a handle secured thereto and a fret board extending therealong, said chamber having a divided face panel including an upper and a lower segment, a tail piece supported on said lower segment, strings connected to said tail piece and extending longitudinally of said handle, 100 said lower segment having a curved limiting edge extending transversely across the chamber, said upper panel segment covering lengths of string varying in an inverse ratio 105 with the vibration-frequencies thereof. 110

7. A musical instrument comprising a resonating base having a stepped side wall, a face panel including a segment affixed to the lower step of the side wall and having a tongue extending therebeyond to the opposite end of the base, a handle secured to said end of the base, a fret board extending along the length of said tongue and of said handle, a head at the end of said handle, a tail piece on said panel segment, strings stretched between said tail piece and said head, and a complementary face panel secured to the raised step of the side wall, under which the strings extend. 115 120

8. A guitar comprising, in combination, a handle having a head, a resonator including a base panel, a side wall extending to greater height at the upper half thereof than at the lower half, a face panel segment closed over the lower part of said wall, a face panel seg- 125 130

ment closed over the upper part of said wall, a tail piece secured at one end to said panel segment, and at the other to said head, and a complementary face panel segment secured 5 upon the upper part of the wall, said wall having a notch through which the strings extend from within the resonator to the handle shank, the contiguous edges of the panel segments determining a resonator 10 mouth aperture.

9. A guitar comprising a resonator base

having a handle protruding therefrom, said base including a panel composed of two segments in parallel planes determining a transverse resonator mouth at their contiguous 15 edges, opening in the direction opposite to that leading to the handle, and a fret board having part of the length thereof extending from the transverse edge of the lower of said panel segments under the upper of said 20 segments to and along said handle.

FREDÉRICO MONACO.
